Attorney

UNITED STATES PATENT OFFICE.

FRED B. GUYETTE AND FREDERICK M. GUNN, OF GUILDFORD, NEW HAMPSHIRE.

BOBBIN-ANTISPLITTING DEVICE.

Application filed April 18, 1922. Serial No. 554,934.

To all whom it may concern:

Be it known that we, FRED B. GUYETTE and FREDERICK M. GUNN, citizens of the United States, residing at Guild, in the 5 county of Sullivan and State of New Hampshire, have invented certain new and useful Improvements in Bobbin-Antisplitting Devices; and we do hereby declare the following to be a full, clear, and exact description 10 of the invention, such as will enable others skilled in the art to which it appertains to make and use the same.

This invention relates to new and useful improvements in attachments for bobbins 15 and has for its primary object the provision of means which may be easily and quickly applied to the stem or shank of a bobbin to prevent splitting of the same when in operation on the spinning frame, consequently 20 rendering a large saving in time and money by increasing the life of a bobbin and which is now extremely short.

Another object of this invention is the provision of a bobbin anti-splitting device 25 of the above stated character which will be simple, durable and efficient, and which may be manufactured and sold at a comparatively low cost.

With these and other objects in view, as 30 will become more apparent as the description proceeds, the invention consists in certain novel features of construction, combination and arrangement of parts as will be herein-after more fully described and claimed.

35 For a complete understanding of our invention, reference is to be had to the following description and accompanying drawing, in which:

Figure 1 is a side elevation, illustrating a 40 bobbin with an anti-splitting device applied thereto constructed in accordance with our invention,

Figure 2 is a fragmentary sectional view, illustrating the same.

45 Referring in detail to the drawing, the numeral 1 indicates as an entirety an ordinary bobbin adapted for use on a spinning machine and by actual experience has been found to easily split while in operation on the spinning machine and to overcome this objection we have provided an anti-splitting device 2. The bobbin 1 includes the usual stem or shank 3 having annular ribs 4 and a

head 5 at its lower end. The stem 3 adjacent to its upper end is provided with an annular groove 6 in which is mounted a reinforcing or strengthening band 7 of the split type and preferably constructed from spring steel or metal. With the band applied to the stem as shown in Figure 1, the latter is prevented 55 from splitting, consequently increasing the life of the bobbin to an indefinite length of time as it has been found that bobbins not reinforced or strengthened only live a comparatively short time consequently causing a 60 large expense, owing to the frequency in which they must be replaced by new bobbins and also causing a delay in the operation of the spinning machine.

While we have shown and described the 70 preferred embodiment of our invention, it will be understood that minor changes in construction, combination and arrangement of parts may be made without departing from the spirit and scope of the invention as 75 claimed.

Having thus described our invention, what we claim is:

1. A device of the character specified including a bobbin stem having the usual annular reinforcing ribs and an annular groove 80 spaced from the ribs and of a width substantially equal to the width of one of said ribs, a split band of resilient material fitted in said groove and of a width and thickness to 85 fill said groove and project beyond the plane of the surface of the stem, said band adapted to reinforce and strengthen the stem.

2. A device of the character specified including a bobbin stem having a groove adjacent one of its ends, said groove having angularly related walls, a split band of resilient metal having a portion to fit snugly within said groove, said band having a portion projecting beyond the upper edge of said groove 95 and rounded so as not to present any sharp edges, said band adapted to reinforce and strengthen said bobbin stem.

In testimony whereof we affix our signatures in presence of two witnesses.

FRED B. GUYETTE.
FREDERICK M. GUNN.

Witnesses:

EFFIE J. CRAIGE,
MILTON H. BRILL.
